UNITED STATES PATENT OFFICE.

SAMUEL B. ROSE, OF NEW YORK, N. Y.

CABINET.

1,069,294.

Specification of Letters Patent.

Patented Aug. 5, 1913.

Application filed June 10, 1912. Serial No. 702,766.

To all whom it may concern:

Be it known that I, SAMUEL B. ROSE, a citizen of the United States, residing in the city, county, and State of New York, have 5 invented certain new and useful Improvements in Cabinets, of which the following is a specification.

My invention relates particularly to that class of cabinets designed to accommodate 10 phonographic disk records or the like.

My improved device contemplates the provision of means for storing such records so that they may be protected from dust and abrasion, and at the same time be readily 15 available for use when desired.

My invention is also designed to furnish a cabinet built on the so-called "elastic" system, whereby the individual file unit may be extended to accommodate a certain maximum 20 number of records and may then be combined with other units, as the demand for filing capacity increases. In accomplishing this end, I provide an individual casing for each record and a collapsible or 25 telescopic frame for receiving and alining the individual record containers, so that as the record user adds to his collection he may adjust the frame to accommodate the increasing number of records he possesses. 30 Furthermore, the frame structures are so designed that they may be stacked, forming uniform shelves or nests of shelves.

In the accompanying drawings which form a part of this specification, Figure 1 is 35 a perspective view of a frame filled to less than its maximum capacity with records and record containers; Fig. 2 is a transverse sectional view through the lower portion of Fig. 1; Fig. 3 is a perspective view of an individual record container and its record; Fig. 4 is an enlarged view of the label or tag which performs the double function of serving to identify each record and of aiding in the withdrawal of it from its container when its use is desired; Fig. 5 is a 40 transverse sectional view of Fig. 4; Fig. 6 is a transverse sectional view, parts being broken away, of a nest of containers; Fig. 45 7 is a perspective view of the extensible frame; Figs. 8, 9, 10 and 11 are, respectively, transverse sectional views at lines 8, 9, 10 and 11 of Fig. 7; Fig. 12 is an enlarged perspective view of the intermediate telescopic member or upright of the frame. 50 Referring to the drawings in detail, the numeral 1 designates the hollow square base

of the frame, to which are secured the uprights 2. Sliding longitudinally in these uprights are intermediate uprights 3, each of which carries a dovetail 4 entering a corresponding slot 5 in the main uprights. The intermediate uprights carry symmetrically arranged dovetails 6 which enter slots or grooves 7 in a third set of upright members 8. There is thus formed a telescopic structure capable of being extended, as shown in Fig. 7, as more and more record containers are inserted. The intermediate sections are provided with two pairs of slots 9 and 10, respectively. Through the former project 70 pins 11 which are secured to the main uprights 2 and which serve to limit the upward travel of the intermediate uprights. Pins 12 secured to the lower extremity of the upper members 8 enter slots 10 and 75 limit the upward travel of the upper members.

A cross-bar or bridge piece 13 is hinged at 14 to one of the upper members and detachably secured by hooks 15, or in any other 80 suitable manner to the other upper member. This cross-bar carries a handle 16. Blocks 17 secured to the upper end of the intermediate members carry the hooks 18 and staples 19, the former adapted to engage the 85 staples 20, and the latter to be engaged by hooks 21 when the blocks enter the sockets 22 formed in the lower member at such times as the device is not in an extended or completely extended position. 90

For carrying each record 23, or similar article to be stored, I provide a packing unit or container 24 comprising a shallow hollow box of such dimensions as completely to inclose the record or other article, and 95 open at one end, 25. A strip of fabric 26 is secured at 27 to the inside of the bottom of each box or container, midway between the sides, and is looped toward the back before being passed above and over the record 100 toward the front, through which it projects, carrying on its extremity a tag 28 which contains a removable name plate 29 bearing the title of the record. It is obvious that when one of these tags is pulled toward the 105 front, it will draw with it the fabric strip and gently but firmly extract the record from its container, making it readily accessible.

Each container bears in each side a notch 110 30 just wide enough to inclose each of the three sets of uprights, as clearly indicated

in Figs. 8, 9, 10 and 11, the uprights being of uniform width, as shown. Each container is therefore locked rigidly against movement in a direction toward or away from the opening in it, and is also locked in a transverse direction by contact with either the main, intermediate or upper uprights, according to what extent the frame has been raised from the base or extended. A solid structure is thus formed at all points, no matter how many containers may be placed at one time within a single frame. Transverse movement is prevented in the case of the intermediate and upper uprights by contact with the inner portion of the slots 30, and in the case of the lower or main uprights by means of the flanges 31 which engage the sides of the containers.

In Fig. 6 I have shown how when one frame is filled to its capacity, another may be placed directly upon it, the handle 16 of the lower system being accommodated within the hollow frame 1, and the cross-piece 13 of the lower system fitting within the notches 32 provided in the frame.

While I have illustrated and described only one specific embodiment of my device, I realize that my invention is susceptible of manifold modifications without departing from the spirit thereof, and I do not wish to be limited to the precise form shown.

Having thus described my invention, I claim:

1. In combination, a base, extensible uprights secured to said base at opposite sides thereof, said uprights being of constant

width regardless of the degree to which they are extended, and a plurality of individual phonographic record containers having notches at opposite sides thereof to engage the said uprights and be locked in alignment thereby.

2. In combination, a base, extensible uprights secured to said base at opposite sides thereof, said uprights being of constant width regardless of the degree to which they are extended, a cross-bar detachably secured to the free ends of said uprights, and a plurality of individual phonographic record containers having notches at opposite sides thereof to engage the said uprights and be locked in alignment thereby.

3. In combination, a base, extensible uprights secured to said base at opposite sides thereof, said uprights being of constant width regardless of the degree to which they are extended, and a plurality of individual phonographic record containers provided with means interlocking with said uprights for holding them in alignment therewith.

4. In combination, a base, telescopic uprights secured thereto, a plurality of individual phonographic record containers, and interlocking means on said uprights and containers for maintaining the latter in fixed alignment within the uprights regardless of the degree to which said uprights are extended.

SAM'L B. ROSE.
